UNITED STATES PATENT OFFICE.

WALTER B. PEARSON, OF CHICAGO, ILLINOIS.

HOLLOW MILL.

SPECIFICATION forming part of Letters Patent No. 733,870, dated July 14, 1903.

Application filed September 12, 1902. Serial No. 123,054. (No model.)

To all whom it may concern:

Be it known that I, WALTER B. PEARSON, a citizen of the United States, and a resident of Chicago, in the county of Cook and State of Illinois, have invented an Improved Hollow Mill, of which the following is a specification.

This invention relates to hollow mills.

Primary objects of the invention are to provide improved and simplified means for adjusting and supporting the cutters and for securing the cutters in the cutter head or body.

A hollow mill of my invention consists of the various features, combinations of features, and details of construction hereinafter described and claimed.

In the accompanying drawings a hollow mill of my invention is fully illustrated.

Figure 1 is a side view of a hollow mill of my invention. Fig. 2 is a front view thereof. Fig. 3 is a partial sectional view on the line 3 of Fig. 2; and Figs. 4 and 5 are side and front views, respectively, of a hollow mill of my invention with the outer section of the head or body thereof removed.

The hollow mill shown in the drawings is of the type designed for use on screw-machines, and consists of a head (indicated as a whole by 1) and a shank 2, adapted to be secured in

30 the turret-head of the screw-machine. The cutters 3 are preferably rectangular in cross-section and are secured in slots 4, formed in the head or body 1 of the tool. As shown, the cutters 3 are loosely fitted to the slots 4 and

35 are secured therein by means of wedges 5, inserted between said tools and the outer sides of said slots 4. As shown, the wedges 5 are tightened in order to clamp the cutters in position by means of screws 6, threaded into the

40 head or body of the tool, collars 7 on which extend inwardly beyond the outer edges of said wedges, so as to draw said wedges into their seats when said screws are tightened.

As preferably constructed the collars 7 are 45 fitted to counterbores 8 in the body of the tool. In this manner the side thrust on the screws 6, due to tightening the wedges 5 and which would be very liable to break said screws if they were unsupported against such side

50 thrust, is transmitted to and sustained by the rigid tool-body. The wedges 5 being set on angles relatively to the screws 6, it is obvious

that the recesses in the faces of said wedges corresponding to the counterbores 8 will have to be sufficiently long to permit of necessary movement of the faces of said wedges relatively to said screws. As shown, they extend entirely across said wedges, forming recessed shoulders 9. By making the counterbores 8 and the recessed shoulders 9 of proper depth 60 the heads of the screws 6 may be made to project only a desired distance beyond the face of the tool-body. As shown, also the sides and bottoms of the slots 4 are formed at an angle to the axis of the head or body of the cutter, thus making provision for adjusting said cutters toward and from the axis of the tool and also providing the desired rake to the cutters. As shown, the cutters have a left-hand rake. As shown, the bottoms and sides of 70 said slots both extend at an angle of about ten degrees to the axis of the head or body of the tool. This angular divergence, however, may be changed to meet varying requirements or as desired. The outer sides of the slots 4 preferably extend parallel with the axis of the tool, the desired wedging action being obtained by forming the bottoms of said slots on an incline. Preferably, also, the outer sides of 75 said slots are circular and concentric with the axis of the tool.

For convenience of construction the head or body of the tool consists of an inner section 10, formed integral with the shank 2, and an outer shell 11, secured in fixed adjustment thereon, the outer surface of the inner section 10 being turned straight and the inner surface of the shell 11 being bored to fit the outer surface of the section 10, being preferably fitted thereto very tight, so that 85 when forced onto the section 10 the frictional engagement thereof will secure them in fixed adjustment. The described construction greatly facilitates the formation of the slots 4, said slots being cut in said section 10 before the shell 11 is secured thereon, the outer sides of said slots being open as they are formed in the section 10 and being closed by the shell 11. This construction likewise facilitates making the wedges 5 and fitting them 90 to the slots 4, the flat sides of said wedges being first formed to fit the flat sides of said slots, after which their outer surfaces are turned off on the same radius as the surface

of the section 10 of the head or body of the tool and of proper thickness.

Formed on the shell 11 is a flange 12, which projects inwardly beyond the edge of the section 10 and is provided with a shoulder 13, which bears against said section 10. Said flange will thus operate to support said shell 11 in position against the pull of the screws 6.

The cutters 3 are adapted to be adjusted inwardly toward the axis of the tool by means of a nut 14, threaded to the shank of the tool, against which the rear ends of said cutters abut. With this construction it is obvious that all of the cutters may be adjusted inwardly simultaneously and equally.

The tool is provided with an axial bore 15, which extends rearwardly from its front face and is adapted to receive the milled end of the article on which the tool is operating. Preferably, also, said bore communicates with a transverse hole or opening 16, formed in the shank 2 thereof, thus making provision for the escape of chips formed by the cutters.

I claim—

1. A hollow mill consisting of a body portion provided with slots, cutters fitted to said slots, wedges inserted between said cutters and a side of said slots and independent means to force each of said wedges into its slot, substantially as described.

2. A hollow mill consisting of a body portion provided with slots, cutters fitted to said slots, wedges inserted between said cutters and a side of said slots, independent means to force each of said wedges into its slot and an adjusting-nut against which the rear ends of said cutters abut, substantially as described.

3. A hollow mill consisting of a body portion comprising an inner section provided with slots and an outer shell secured in fixed adjustment thereon, cutters fitted to said slots, wedges inserted between said cutters and said outer shell and independent means to force each of said wedges into its slot, substantially as described.

4. A hollow mill consisting of a body portion provided with slots, cutters fitted to said slots, wedges inserted between said cutters and a side of said slots, screws threaded into the body portion of said hollow mill and collars thereon which extend over the front ends of said wedges whereby said wedges may be forced into said slots, substantially as described.

5. A hollow mill consisting of a body portion comprising an inner section provided with slots and an outer shell secured in fixed adjustment thereon, cutters fitted to said slots, wedges inserted between said cutters and a side of said slots, screws threaded into the body portion of said hollow mill and collars thereon which extend over the front ends of said wedges whereby said wedges may be forced into said slots, substantially as described.

6. A hollow mill consisting of a body por-

tion comprising an inner section provided with slots and an outer shell secured in fixed adjustment thereon, being provided with an inwardly-projecting shoulder which bears against the rear side of said inner section, cutters fitted to said slots, wedges inserted between said cutters and said outer shell, screws threaded into said outer shell and collars thereon which extend over the front ends of said wedges whereby said wedges may be forced into said slots, substantially as described.

7. A hollow mill consisting of a body portion comprising an inner section provided with slots and an outer shell secured in fixed adjustment thereon, cutters fitted to said slots, wedges inserted between said cutters and said outer shell, independent means to force each of said wedges into its slot and an adjusting-nut against which the rear ends of said cutters abut, substantially as described.

8. A hollow mill consisting of a body portion comprising a cylindrical inner section provided with slots and an outer shell secured in fixed adjustment thereon, said outer shell being provided with a shoulder against which the rear side of said inner section bears, cutters fitted to said slots, wedges inserted between said cutters and said outer shell, screws threaded to said outer shell, collars on said screws which project over the front ends of said wedges whereby said wedges may be forced into said slots and an adjusting-nut against which the rear ends of said cutters abut, substantially as described.

9. A hollow mill consisting of a body portion provided with slots, the bottoms and lateral sides of which are formed at angles to the axis of the body of said tool, cutters fitted to said slots, wedges inserted between said cutters and the sides of said slots and independent means to force each of said wedges into its slot, substantially as described.

10. A hollow mill consisting of a body portion comprising an inner section provided with slots, the bottoms and lateral sides of which are formed at angles to the axis thereof and an outer shell secured in fixed adjustment thereon, cutters fitted to said slots, wedges inserted between said cutters and said outer shell, independent means to force each of said wedges into its slot and an adjusting-nut against which the rear ends of said cutters abut, substantially as described.

11. A hollow mill consisting of a body portion comprising an inner section provided with slots, the bottoms and lateral sides of which are formed at angles to the axis thereof and an outer shell secured in fixed adjustment thereon, said outer shell being provided with a shoulder which bears against the rear side of said inner section, cutters fitted to said slots, wedges inserted between said cutters and said outer shell, screws threaded into said outer shell, flanges thereon which extend over the front ends of said wedges and an adjusting-nut against which the rear

ends of said cutters abut, substantially as described.

12. A hollow mill consisting of a body portion provided with slots, cutters fitted to said slots, wedges inserted between said cutters and the sides of said slots, screws threaded into said tool-body and flanges thereon which extend over the front ends of said wedges, the tool-body being provided with counterbores to which said flanges are fitted and said wedges being provided with corresponding recessed shoulders, substantially as described.

13. A hollow mill consisting of a body portion provided with slots the bottoms and lateral sides of which are formed at angles to the axis of the body of said tool, cutters fitted to said slots, wedges inserted between

said cutters and the sides of said slots, screws threaded into said tool-body parallel with the axis of said tool, flanges thereon which extend over the front ends of said wedges, the tool-body being provided with counterbores to which said flanges are fitted and said wedges being provided with corresponding recessed shoulders, substantially as described.

In testimony that I claim the foregoing as my invention I affix my signature, in presence of two subscribing witnesses, this 19th day of August, A. D. 1902.

WALTER B. PEARSON.
